UNITED STATES PATENT OFFICE.

FRANÇOIS CHEVILLAT, OF BIENNE, SWITZERLAND, ASSIGNOR TO SOCIÉTÉ ANONYME LOUIS BRANDT & FRERE, OF BIENNE, SWITZERLAND, A CORPORATION OF SWITZERLAND.

MEANS FOR SECURING WATCH-MOVEMENTS IN THEIR CASES.

SPECIFICATION forming part of Letters Patent No. 783,611, dated February 28, 1905.

Application filed December 31, 1903. Serial No. 187,272.

To all whom it may concern:

Be it known that I, FRANÇOIS CHEVILLAT, a citizen of Switzerland, residing at Bienné, Canton of Berne, Switzerland, have invented 5 certain new and useful Improvements in Means for Securing Watch-Movements in Their Cases, of which the following is a clear, full, and exact description.

My invention relates to an improvement in 10 the construction of watches, and more particularly to the means employed for securing the movements within the cases.

The object of my invention is to improve 15 and simplify the constructions employed.

My invention will be pointed out in the 20 claims terminating this specification.

The drawings accompanying herewith illustrate the embodiment of my invention which 25 is now preferred by me.

Figure 1 is a central section, and Fig. 2 is a 30 bottom plan view with the case-center omitted.

A represents a watchcase-center, preferably 35 having near its back surface an inward projection or flange *a*, adapted to coöperate with other parts to secure the movement in place.

The movement as herein shown comprises a 40 pillar or "front" plate *p*, a plate *r*, which may be either the dial itself or a dial-plate, and the movement-case *E*. *D* is a dust-band or movement-ring. The exact construction of these 45 parts is not material, however. They may be combined together as a single integral member or be subdivided into separable parts in any way known or common to the art or dictated by expediency and may otherwise vary 50 in their features of construction.

The dust-band is preferably provided with 55 an inturned edge *d* at its rear side to rest on a flange *a* and preferably has an internal shoulder adapted to support a flange or projection *d* on the pillar-plate.

The movement is held in place within the 60 watchcase-center by one or more locking bolts or screws *c c* and preferably, also, a coöperating spacing member or members, said bolts drawing the movement down to position and defining this position by engagement of a part 65 of the watchcase-center, as the flange *a*, be-

tween the head of the bolt and the spacing member.

The movement is preferably provided with 70 one or more recesses *e f* in its periphery and adapted to receive the spacing members *b b*, which project slightly beyond the periphery of the movement. These spacing members *b* 75 should preferably fit the recess, whereby they are held against side rocking, and so serve to hold the bolts against similar motion. This side engagement may be only by a flange or head upon the back end of the spacing-sleeves. 80 By varying the dimensions of this spacing member, which ordinarily would be made of a simple and cheap construction, the movement may be made to fit centers of different thickness. The securing-screws are provided 85 with enlarged heads *c*, preferably cut away at one side, so that they may be turned so as to project beyond the periphery of the movement at that point, so as to overlap a portion of the case-center, as herein shown, 90 this portion being the flange *a*. The spacing members, as herein shown, may be collars or sleeves *b b*, which are located in said recesses and surround the bolts, one end engaging a part of the movement, preferably the pillar 95 or front plate *p*, into which the bolt screws, and the other end engaging the upper side of the flange *a*. Such a spacing member is cheap in first cost and may be easily reduced in length to obtain an exact fit. The dust-band 100 *D* may also be made of whatever thickness may be necessary to make the movement fit the case. By this expedient watch-movements may be made to fit any case approximating to them in size, if not smaller.

It will be observed that the case-center shown has an inward extension *a* at the back and another inward extension at the front, within which the dust-band fits. The front movement-plate or pillar-plate *p* is detached 105 from—that is, is not attached to—this front extension. The watch-movement has a peripheral flange *d*, preferably, as in this case, formed by the front or pillar plate, so as to rest upon the supporting-ring *D*. The dust-band *D* forms a support for the movement 110

which is outside of the periphery of the movement below this flange *d*. The heads of the screws *c* are adapted to project (when they are turned into the position shown at the left 5 of Fig. 1) outwardly beyond the periphery of the movement at the lower edge of the dust-band, and the screws are long enough so that when their threads are in engagement with the movement there will be a space left 10 between the upper side of the head of the screw and the lower edge of the dust-band *D* in order to receive the flange or extension *a* so that the dust band or support may be seated upon the upper side of this extension 15 with the head of the screw below it. The screws *c* preferably are of a length sufficient to screw into the front plate *p*. This is of a distinct advantage, because by it the strain comes directly upon the front plate and it is 20 not so apt to be sprung as would be the case if the screws were merely tapped into the lower part of the movement and did not extend into the front plate.

It will be obvious that many changes may 25 be made in the construction shown without departing from the scope of my invention as claimed, and I therefore do not limit myself to the particular construction described and illustrated.

30 What I claim is—

1. The combination with a watchcase-center having a flange toward its back of smaller diametral opening than the opening at its front side, a pillar-plate adapted to enter the case-center from the front side, and means for holding 35 the pillar-plate in place, comprising adjustable tension members secured to the pillar-plate and engaging the back or outer side of the said flange of the case-center, and a separable spacing member engaging the front side of said flange and the pillar-plate.

2. A watch-movement having a flange at its periphery, a surrounding dust-band having an internal shoulder against which said flange 45 rests, a screw tapped into the under side of said movement and having a head located below the lower edge of said band and adapted to project laterally beyond the periphery of said movement and the lower edge of said 50 band and adapted to clamp a portion of said case.

3. A watch-movement having a flange at its periphery, a surrounding dust-band having an internal shoulder against which said flange 55 rests, said band being turned inwardly at its rear side, said movement having one or more recesses in its periphery, a screw tapped into the under side of said movement and located in said recess and having a head located below 60 the lower edge of said band and adapted to project beyond the periphery of said movement, and a spacing member located in said recess above the head of said screw and also projecting beyond the periphery of said movement.

65

4. In combination, a watch case-center having an inturned flange at its rear side, a watch-movement having a flange at its periphery, a surrounding dust-band having an internal shoulder against which said latter flange rests, 70 said dust-band being turned inwardly at its rear side and resting on the flange on said case-center, said movement having one or more recesses in its periphery, a screw tapped into the under side of said movement and located in said recess and having a head located below the lower edge of said band and adapted to project beyond the periphery of said movement and the inner periphery of said flange on 75 said case-center, whereby said flange on said case-center is held between said dust-band and head.

5. In combination, a watch case-center having an inturned flange at its rear side, a watch-movement, a surrounding dust-band supporting said movement, said dust-band resting on the upper side of said case-center flange, said movement at its rear side being adapted to project into the opening formed by said case-center flange, a spacing member located between 80 said dust-band and movement and resting against the upper portion of said case-center shoulder and supporting said movement, and one or more screws tapped into the under side of said movement and having a head located below the lower edge of said case-center flange and adapted to project beyond the same 85 whereby said latter flange is held between said spacing member and said head.

6. In combination, a watch-movement having one or more recesses in its periphery, a screw tapped into the under side of said movement and having a head adapted to project beyond the periphery of said movement, and a spacing member located in said recess above 90 the head of said screw and also projecting beyond the periphery of said movement.

7. In combination, a watch-movement having one or more recesses in its periphery, a screw tapped into the under side of said movement and having its shank located in said recess, and having a head adapted to project beyond the periphery of said movement, and a spacing member also located in said recess above the head of the said screw and also projecting beyond the periphery of said movement.

8. A watch-movement having a flange at its periphery, a surrounding dust-band having an internal shoulder against which said flange rests, said movement having one or more recesses in its periphery, a screw tapped into the under side of said movement and having a head located below the lower edge of said band and adapted to project beyond the periphery of said movement, and a spacing member located in said recess above the head of said screw and also projecting beyond the periphery of said movement.

9. In combination, a watchcase-center hav-

130

ing an inturned flange at its rear side, a watch-movement, a surrounding dust-band supporting said movement, said dust-band resting on the upper side of said case-center flange, said 5 movement at its rear side being adapted to project into the opening formed by said case-center flange, and one or more screws tapped into the under side of said movement and having a head located below the lower edge of said 10 case-center flange and adapted to project beyond the same whereby said latter flange is held between said dust-band and said head.

10. The combination with a watchcase-center having a flange towards its back of smaller 15 diametrical opening than the opening at its front side, a movement adapted to enter the case-center from the front side and project into the opening formed by said case-center flange, and means for holding the movement 20 in place, comprising adjustable tension members secured to the movement and engaging the back or outer side of the said flange of the case-center, and one or more separable spacing members engaging the front side of said 25 flange and the movement.

11. A watch-movement having a flange at its periphery, a surrounding dust-band having a shoulder against which said flange rests, said movement having one or more recesses in its 30 periphery, one or more screws tapped into the under side of said movement and having a head located in said recess and below the lower edge of said band and adapted to project beyond the periphery of said movement at that 35 point.

12. As a means for fastening a watch-movement to its case from the back of the watch, the combination of a case-center having front and back inward extensions, a watch-movement 40 sufficiently small to be inserted from the front, said movement including a front movement-plate detached from said front extension and a dust-band sufficiently small to come within the front extension and rest on the 45 back extension, a screw, a threaded end of which screws into said movement-plate and the head of which bears against the said back extension so as to draw the movement-plate toward said back extension upon screwing up 50 the screw, said dust-band being clamped between said movement-plate and said back extension.

13. A watch-movement having a peripheral flange, a movement-support outside of said 55 movement below said flange, and one or more screws inside of said support and screwing into said movement from the rear and having a head below, and projecting outwardly beyond the periphery of said movement at, the lower 60 edge of said support, said screw being of a length sufficient to form a space between said support and head while the thread of said screw is in engagement with said movement, said space being adapted to receive a part of 65 a watchcase.

14. A watch-movement having a peripheral flange, said movement including a front plate, a movement-support in the form of a ring outside of said movement below said flange, and one or more screws inside of said ring and 70 screwing into said front plate from the rear and having a head below, and projecting outwardly beyond the periphery of said movement at, the lower edge of said ring, said screw being of a length sufficient to form a space 75 between said ring and head while the thread of said screw is in engagement with said front plate, said space being adapted to receive a part of a watchcase.

15. In a watch, the combination with the 80 case thereof, of a movement sufficiently small to be set into the said case from the front of the same, a movement-support forming a seat for the movement and resting upon the said case at the back thereof, and one or more 85 screws passing from rear to front, entering the said movement and coacting with the said case at the back thereof to draw the movement rearward and seat the same upon the said movement-support and in turn seat the 90 said movement-support upon the said case at the back thereof, said movement being unsupported by said case at the front thereof.

16. In a watch, the combination with the 95 case thereof, of a movement having a front plate, said movement being sufficiently small to be set into the said case from the front of the same, a movement-support forming a seat for the movement and resting upon the said case at the back thereof, and one or more 100 screws passing from rear to front, entering the front plate of the said movement and coacting with the said case at the back thereof to draw the movement rearward and seat the same upon the said movement-support, and in 105 turn seat the said movement-support upon the said case at the back thereof, said movement being unsupported by said case at the front thereof.

17. In a watch, the combination with the 110 case thereof, of a movement having a front plate, said movement being sufficiently small to be set into the said case from the front of the same, a movement-support in the form of a ring surrounding the movement and resting 115 upon the said case at the back thereof, and one or more screws passing from rear to front, entering the front plate of the said movement and coacting with the said case at the back thereof to draw the movement rearward and seat the front plate thereof upon the said ring, and in turn seat the said ring upon the said case at the back thereof, said movement being 120 unsupported by said case at the front thereof.

Signed at Biel (Bienne) this 7th day of December, 1903. 125

FRANÇOIS CHEVILLAT.
